UNITED STATES PATENT OFFICE.

FRANK BUCHTER, OF NEW BEDFORD, MASSACHUSETTS, ASSIGNOR TO THE MORSE TWIST DRILL AND MACHINE COMPANY, OF SAME PLACE.

MACHINE FOR MAKING TWIST-DRILLS.

SPECIFICATION forming part of Letters Patent No. 320,456, dated June 23, 1885.

Application filed March 18, 1885. (No model.)

To all whom it may concern:

Be it known that I, FRANK BUCHTER, of New Bedford, in the county of Bristol and State of Massachusetts, a citizen of the United States, have invented certain new and useful Improvements in Machines for Manufacturing Increased-Twist Drills, of which the following is a specification.

In machines of this class, in which the drill-blank is carried forward and rotated while operated upon by fixed cutters, there are three motions to be imparted to the drill-blank. The first of these is a regular or constant forward motion past the cutter; the second is the rotation of the drill-blank while passing the cutter, and the third is the gradual and regulated increase of forward motion of the rotating drill-blank, this last being required to obtain what is known as the "increased twist."

My present invention relates to improvements in the devices by which these motions are obtained, and also in improvements in the arrangement of the cutters or mills which coact with the rest of the machine to form the drill.

In the accompanying drawings, Figure 1 is a front elevation, and Fig. 2 a side elevation, of a machine embodying my present improvements, in the form now best known to me. Fig. 3 is a top plan view of the same, and Fig. 4 a detail of a part of the structure, as will be hereinafter explained. Figs. 5 and 6 are top plan views of the machine upon the plane of the lines $x x$ and $y y$, respectively, in Fig. 1.

I will describe first the mechanism for giving the drill its constant forward motion.

A represents the main frame of the machine, within which a carriage, B, is arranged to rise and fall, being guided by grooves, as shown in Fig. 5. The regular forward or upward motion of the drill-blank is derived from the forward or upward motion of this carriage, and this in turn comes from the revolution of a pair of screws, $a a$, (best seen in Fig. 1,) provided near their lower ends with gears a' , which are driven by a central gear, b , (see Fig. 6,) upon an upright shaft. This shaft also carries a gear meshing with and driven by a worm on the shaft c , which shaft

is provided with a pulley, C, (see Figs. 1 and 6,) where the power is applied.

The rotation of the drill-blank coincidently with its forward motion is obtained as follows: The drill-blank is held within a loose sleeve or bushing, D, located in the carriage B, and free to rotate therein. This sleeve D is rotated by means of a gear, d' , which meshes with an intermediate gear, d , supported upon an arm extending from the carriage B, and this intermediate gear is in turn driven by a pinion, q , upon a shaft carrying a gear, Q, which meshes with and is driven by a pinion, e , upon a second vertical shaft, E. This shaft E also carries at its lower extremity a gear, F, (see Fig. 6,) meshing with and driven by a gear, f , which in turn takes its motion from the worm gear-shaft and pulley c C, before mentioned.

The third motion to be imparted to the drill-blank is the gradually-increased forward motion above mentioned. This is obtained by means of devices best shown in Fig. 4, wherein, as will be seen, the bases or lower extremities of the screw-rods $a a$ are represented as resting upon levers G, which rest upon and are operated by cams H. The pitch of these cams corresponds with the increased or forward movement required to produce the increased twist. These cams are mounted on a common shaft, h, which is geared to and driven by a depending worm-shaft, I, (see Figs. 1 and 4,) this worm-shaft I deriving its motion from the main source of power, C c, through the gearing f and F and the interposed gear i. (See Fig. 6.) The screws $a a$ are in splined connection with their driving-gears, (see Fig. 4,) to allow for their upward motion under the influence of the lever G, as described. The pinion e is also splined upon the shaft E to allow for the forward or upward motion of the carriage B and the train of gearing carried by it. The mills or cutters K K are of ordinary construction, and mounted upon adjustable bearings in the ordinary manner. They are driven by worm-gears and shafting of their own, as shown in Figs. 1, 2, and 3. They have, however, one peculiar feature, which I will now describe. Inasmuch as the depth of the grooves in the drill gradually decreases

90
95
100

from the point toward the butt or heel, it is desirable that the cutters or mills K K should be gradually adjusted apart as the cutting progresses to produce such a gradual decrease 5 in the depth of cut. For this purpose I mount the cutters upon blocks L L, traveling in slides crosswise of the machine, or so that they may be brought toward or away from the central line of the drill-blank, and to these 10 blocks I attach screws l l. (See Fig. 3.) These screws are respectively right and left handed. They are caused to revolve by pinions N N, meshing in and driven by a rack, O. This rack is, for convenience, made in two 15 parts, centrally pivoted, as shown in Fig. 2, and so that it may be thrown out of connection with the pinions N N, if desired.

As it is desirable that the motion of the cutters apart to reduce the depth of the groove 20 in the manner just described should be regulated by and correspond with the gradual advance of the drill-blank, the rack O may be arranged to be operated by an arm, P, against which a part of the carriage B bears. In this 25 way, as will be seen, the gradual forward or upward motion of the carriage B acting against the arm P produces a lateral motion of the rack O, and this, by means of the pinions N, screws l, and sliding carriages L, moves the 30 cutters K apart.

As the whole operation of cutting the grooves of the drill is performed by its passing once upward or forward by the cutters K, it is obvious that the machine must be driven 35 slowly. With this fact in mind it will be easy to understand the operation of the machine, which is as follows: The carriage B with its connected parts and the screws a a being at their lowest point in the machine, the shank 40 of the drill-blank is inserted in the sleeve D, and the cutters K K are set at the proper distance apart to commence their work upon the drill-blank. Power being now applied to the pulley C, and also to the pulleys which drive 45 the cutters, the rotation of the screws a a moves the carriage B and carries the drill-blank slowly upward or forward past the revolving cutters, and at the same time the drill-blank is slowly rotated through the agency of 50 the shaft E and its gearing. Simultaneously with these operations, the rotation of the cams H H produces an additional forward or upward movement of the screws a a, and consequently of the carriage B and the drill-blank. 55 Moreover, as the carriage B gradually moves forward or upward, it strikes against and operates the arm P and thus moves the rack O, thereby gradually moving the cutters K K apart as the cutting progresses. After the 60 whole of the drill-blank has passed by the

cutters, the forward motion of the machine is stopped, its work having been accomplished.

The return of the carriage B and screws a a to their original or lowest position is accomplished by imparting a reverse motion to the 65 gears which drive them. This is done by means of a hand-wheel, S, upon the upper part of the shaft E, Fig. 1, by turning which all the gearing may be made to operate in the reverse direction. The cutters and their operating-rack O may also be returned to their original positions by means of hand-wheels R R operating the screws l l. These hand-wheels are shown in Figs. 1 and 3.

In order to adapt the machine to various 75 sizes of drill, intermediate gearing of various sizes may be used in the train of gearing employed to rotate the sleeve D; also, the rate of forward motion of the screws a a may be varied for any particular size of drill by changing the intermediate gear, i. (See Fig. 6.)

I claim—

1. In a machine for making twist-drills, the forwarding mechanism for giving an accelerated forward motion to the drill-blank 85 past the cutters, it consisting in the combination, with the forwarding-screws, of levers which bear against and lift the forwarding-screws, and cams mounted upon a suitable driving-shaft, the cams being arranged to bear 90 against and lift the levers, all substantially as herein set forth.

2. In a machine for making twist-drills, the combination, with a rotary sleeve which carries and rotates the drill-blank, of a rotating shaft, E, said shaft being connected by intermediate-gearing, substantially as described, both with the drill-rotating sleeve and also with the main source of power of the machine, all substantially as herein set forth, and for 95 the purposes herein specified.

3. In a machine for making twist-drills, the combination, with cutters arranged to be moved laterally toward and away from the central line of the drill-blank, of right and left 105 handed screws l l, their pinions N N, and a rack, O O, for actuating the pinions, all substantially as herein set forth.

4. In a machine for making twist-drills, the combination of the cutters K, mounted in laterally-movable supports, the screws l l, pinions N, rack O, arm P, and forwardly-moving carriage B, all substantially as herein set forth.

In testimony whereof I have hereinunto subscribed my name this 12th day of March, A. 115 D. 1885.

FRANK BUCHTER.
